PILOT BIT FOR EARTH AUGERS

Gerald A. Petersen, San Francisco, Calif.

Application November 1, 1949, Serial No. 124,888

1 Claim. (Cl. 255—61)

1

My invention relates to tools for boring in the earth, particularly, and is especially concerned with a power driven tool used ordinarily as an adjunct to a larger earth auger and is particularly concerned with the part of the earth auger which first encounters the earth and which leads the remaining part of the auger as it advances into the earth.

In power boring of earth holes particularly in ground that is irregular in make up and in characteristics, it is necessary to have a pilot bit for the earth auger which excavates cleanly, which clears itself of the materials being excavated, which wears extremely well, since it is normally the first to encounter abrasive material, and especially one which is capable of digging or excavating at least as fast as the remainder of the auger can excavate once the initial path has been broken.

It is an object of my invention to provide an improved pilot bit for earth augers which will have the various attributes mentioned above.

Another object of my invention is to provide a pilot bit for earth augers effective over a long period of time, with little deterioration due to abrasion and wear and effective to operate with moderate power at relatively great speed.

Another object of my invention is to provide a pilot bit for an earth auger effectively usable with earth augers already available.

Another object of my invention is to provide a pilot bit effective to operate in various different soils normally encountered.

A still further object of my invention is to provide a pilot bit readily handled by workmen under the usual conditions and readily fabricated for economical production.

Other objects, together with the foregoing are attained by the embodiment of the invention described in the accompanying description and illustrated in the accompanying drawings in which:

Figure 1 is a side elevation of my pilot bit as it is provided for attachment to an earth auger.

Figure 2 is a top plan view of the pilot bit as shown in Figure 1.

Figure 3 is a bottom plan view of the pilot bit as shown in Figure 1.

While it is susceptible to use in many different environments and can be readily varied within the scope of the claims to meet different circumstances in use, my pilot bit is especially useful in conjunction with an earth auger of the type shown in my co-pending application entitled "Earth Auger," filed August 5, 1946, Serial No.

2

688,436, now Patent 2,578,014, issued December 11, 1951. That earth auger includes a rotary member having a central tube with a non-circular cross section designed to be driven by a squared shaft from a suitable power source and at the bottom includes an attachment means for a pilot bit, the pilot bit being approximately a quarter the diameter of the main auger.

In the present instance, the earth auger is represented in broken lines as having a central sleeve 6 pierced by a square or rectangular central passageway 7 and designed to rotate about a longitudinal axis 8. Designed to fit in the sleeve 6 is my pilot bit. This bit includes a shank portion 9 largely circular in its outline although having a pair of flat sides 11 and 12. The shank includes a cross key 13 designed to interfit in a suitable transverse slot in the bottom of the driving sleeve 6 and includes furthermore a central tongue 14 extending upwardly into the bore of the sleeve 6. The pilot bit is fastened in place by a through pin 16 engaging the sleeve and also passing through an aperture 17 piercing the tongue. This attachment is readily made when the pilot bit is first assembled with the earth auger so that the pilot bit is held in place and is caused to rotate with the earth auger about the axis 8. When it is to be removed, the pilot bit is readily detached after withdrawal of the pin 16.

Preferably formed integrally with the shank 9 and in most instances cast in one piece therewith are blade members 21 and 22, respectively. In the present instance, two blade members are disclosed as representative of any chosen number and since each of the blade members is identical with the others the description of one applies equally to the others. The blade member 22, for example, depends from the shank 9 in a generally downward direction, as seen in Figure 1, and as it descends or depends, it advances in the direction of rotation of the bit as a whole, as represented by the arrow 23. The path of the surface or contour of the blade member 22 is approximately helical although it deviates from a true mathematical helix in that its cross-section in any plane normal to the rotational axis is a right line in advance of a line through the axis 8 in that plane.

The blade 22 terminates on its leading, cutting edge 24 in a plane, represented by the line 26 in Figure 1, that is normal or perpendicular to the axis 8. The leading edge 24 is a straight or right line in the plane 26 and is spaced or displaced from a line 27 (Figure 3) passing through the axis 8 by a predetermined amount 28, the di-

rection of displacement being in the direction of advance as indicated by the arrow 23. The leading edge 24 does not extend as far as the axis 8 itself but, being displaced from such axis, is in fact tangent to an imaginary circle 29 having the axis 8 as a center and disposed in the plane 26.

The shape of the blade member 22 is such that the blade is relatively thick throughout most of its length but adjacent its leading edge 24 rapidly thins so that the line trace results. Furthermore the leading edge 24 does not extend for a full diameter 31 of the hole 32 bored by the bit. Rather, the leading edge 24 extends inwardly to a point 33 approximately on the tangent circle 29 at which point the envelope curve of the blade member extends inwardly and upwardly along an approximately helical line 34, as seen in Figure 1, to provide a central V-shaped, relieved recess symmetrical about the axis 8 of the bit. The outer margin 36 of the blade member 22 may either lie on the periphery of the hole 32, or may recede from the leading edge 24 toward the center in a spiral plan, as shown in Figure 3.

In operation when the pilot bit is on an earth auger and is rotated in the direction of the arrow 23, the leading edges 24 of the blades 21 and 22 advance into and cut the earth not with a straight ahead motion but rather with a component which is transverse or lateral so that a shearing action takes place and an annular path is cut. The central portion of the pilot bit near the V-shaped central notch defined by the edges 34 does not cut but rather breaks the earth away as the bit advances. It has been found that this is a superior means for removing the central part of the bore. The material which has been removed by the combination advancing and shearing or sliding cutting action rides upwardly over approximately helical surfaces of the blade members 21 and 22 and travels upwardly into the earth auger from which it is discharged.

A pilot bit constructed as indicated is cheap to manufacture since it is cast in a single piece, is readily mounted and demounted by workmen at the site with the customarily available tools, by virtue of its shearing action wears a long time

relatively under all sorts of digging conditions, and because it is relieved at its center advances rapidly into the earth without being held back by a central block and provides a generally improved operation for devices of this sort.

I claim:

A pilot bit for earth augers comprising a shank adapted to rotate in a predetermined direction about an axis to bore a hole of predetermined circumference, a pair of identical blade members depending from said shank, each of said blade members having a helical leading surface generated throughout its length by a right line moving in a downward direction in a substantially helical curve, said line being tangent to a small circle concentric with said axis and located between the perimeter of said bore and said axis, said leading surface terminating in a leading edge disposed in a plane perpendicular to said axis on a right line tangent to said small circle, said leading edge extending from said small circle to a point on said circumference of said hole, the outer margins of said blade members receding from said points on said circumference to a lesser diameter in a spiral plan as said margin ascends from said leading edge.

GERALD A. PETERSEN.
